Inventor:

Mary A. Taylor.

UNITED STATES PATENT OFFICE.

MARY A. TAYLOR, OF CINCINNATI, OHIO.

IMPROVEMENT IN WASH-BOILERS.

Specification forming part of Letters Patent No. **56,830**, dated July 31, 1866.

To all whom it may concern:

Be it known that I, MARY A. TAYLOR, of Cincinnati, Hamilton county, and State of Ohio, have invented certain new and useful Improvements in Wash-Boilers; and I do hereby declare the following to be a full, clear, and exact description thereof, reference being had to the accompanying drawings, making part of this specification.

My invention consists in the addition to an ordinary wash-boiler of a set of drainers, which contain the clothes and which are adapted to be placed inside of the boiler, whereby the clothes are prevented from soiling and scorching by contact with the bottom of the vessel, and whereby, by simply lifting one drainer out of the boiler and resting it on top of the other one, the greater portion of the water is enabled to run back into the boiler.

The arrangement also enables the boiling of white and colored clothes separately in the several drainers.

In the accompanying drawings, Figure 1 is a perspective view of a wash-boiler provided with my improvements, the lid being removed. Fig. 2 is a perspective view of one of my drainers, so placed as to show its perforated bottom; and Fig. 3 is a vertical longitudinal section of a wash-boiler, representing one of the drainers as being elevated so as to free it from the water.

A represents an ordinary wash-boiler, which may be provided with the customary drop or pit B and handles C C'.

D and E are two drainers, of a proper size to fit snugly within the boiler A, and these drainers are provided with perforated and concave or dishing bottoms D' E' and handles d' d' and e' e'.

Two or more drainers may be employed for each boiler, depending upon the size of the latter, and, if preferred, the perforated bottoms may be omitted and wire-cloth substituted for them.

The drainers are provided with downwardly-projecting flanges F and G, which rest upon the horizontal ledge or shoulder H of the wash-boiler pit, thereby allowing a space between the bottoms of the boiler and strainers

for hot water and also for sediment to settle in, and preventing any possible scorching or soiling of the clothes.

Operation: The wash-boiler A being placed upon the stove and supplied with water, the drainers D and E are filled with the clothes and immersed in the boiler, and as the articles rest entirely upon the perforated concave bottoms D' E' of the drainers, they are thus prevented from coming in contact with the highly-heated bottom of the boiler.

The perforated bottoms D' and E' of the strainers permit a constant and thorough circulation of hot water through said strainers, and their contents and the dirt and sediment extracted from the clothes by the boiling operation pass through the perforations, and their greater specific gravity compels them to settle at the bottom of the boiler, instead of being boiled into the lower stratum of clothes, as is always the case with the old style of wash-boilers.

The clothes having been boiled a sufficient length of time, either of the drainers D or E is lifted from the boiler A, and allowed to rest for a few moments upon the top of the remaining drainer, until the water which was contained in it has all escaped through its perforated bottom, when it is removed from the boiler and its contents emptied into the clothes-basket or wash-tub.

The drainer being thus emptied of its contents, it is returned to its original position in the boiler, and when the other drainer is lifted out it is allowed to rest for a few moments on the top of the empty one, until all the water escapes from it, when the clothes are also removed from said drainer into the wash-tub.

As the clothes are removed from the boiler to the tub in a drainer from which the water has entirely escaped, all slopping of hot water over the floor or on the person of the operator or bystander is prevented and there is no danger of punching holes in the clothes by lifting them from the boiler with the old-fashioned clothes-stick.

The provision of the two drainers enables the operator to separate the fine from the coarse clothes in the boiler, and the old from new

fabrics, thereby preventing the former from discoloring the latter by coming in contact with them during the boiling operation.

These drainers can be added to any wash-boiler at a mere nominal cost, and are so simple in their construction that they can be made by any country tinner.

This invention entirely dispenses with the lifting of hot, saturated, and streaming clothes, which is well known to constitute the most severe and injurious labor of washing.

I claim herein as new and of my invention—

A plurality of receptacles, D E, each constructed with a perforated bottom and adapted to fit within a wash-boiler and operate, in connection with each other, in the manner and for the purposes herein described.

In testimony of which invention I hereunto set my hand.

M. A. TAYLOR.
